United States Patent

Des. 237,478
Patented Nov. 4, 1975

237,478

BICYCLE

D. Lee Carpenter and James E. Cotter, Dayton, Ohio,
assignors to The Huffman Manufacturing Company,
Miamisburg, Ohio

Filed June 26, 1974, Ser. No. 483,249

Term of patent 14 years

Int. Cl. D12—11

U.S. Cl. D12—111

FIG-1

FIG-2

FIG-3

FIG-4

FIG-5

FIG-6

FIG. 1 is a front perspective view of a bicycle embodying our new design;

FIG. 2 is a rear perspective view thereof showing the side opposite to that in FIG. 1;

FIG. 3 is a side elevational view thereof of the side shown in FIG. 1;

FIG. 4 is a top plan view thereof;

FIG. 5 is a front elevational view thereof; and

FIG. 6 is a rear elevational view thereof.

We claim:

The ornamental design for a bicycle, substantially as shown and described.
